Specification for Design.

Patented Jan. 13, 1914.

Application filed October 31, 1913. Serial No. 798,600. Term of patent 7 years.

To all whom it may concern:

Be it known that I, EDWARD W. STIFEL, a citizen of the United States of America, and resident of Wheeling, county of Ohio, and State of West Virginia, have invented a new, original, and ornamental Design for Printed Denims, of which the following is a specification, reference being had to the accompanying drawing, forming a part thereof.

The figure is a plan view of a portion of printed denim illustrating my new design.

The design consists of parallel bands or stripes of uniform width formed on a solid-color woven fabric by printing thereon in contrasting color short fine lines or dots which present the appearance of scattered threads of said contrasting color interwoven in the fabric, each of said bands or stripes being bordered on opposite sides by a line or row of relatively larger, substantially circular, printed dots in the contrasting color. Adjacent rows of dots are separated by relatively narrow unprinted portions of the solid color fabric.

I claim:

The ornamental design for a printed denim, as shown and described.

In testimony whereof, I affix my signature in presence of two subscribing witnesses.

EDWARD W. STIFEL.
